[57] CLAIM

The ornamental design for a hanger for bird feeder, as shown.

DESCRIPTION

FIG. 1 is a perspective view of the hanger for bird feeder of our invention;
FIG. 2 is a front elevational view thereof;
FIG. 3 is a side elevational view thereof;
FIG. 4 is a back elevational view thereof;
FIG. 5 is a top view thereof;
FIG. 6 is a bottom view thereof;
FIG. 7 is a perspective view of a modified embodiment of the hanger for bird feeder of our invention;
FIG. 8 is a front elevational view thereof;
FIG. 9 is a back elevational view thereof;
FIG. 10 is a side elevational view thereof;
FIG. 11 is a top view thereof; and,
FIG. 12 is a bottom view thereof.

The broken lines in FIGS. 1 and 7 are for purposes of illustration only and form no part of the claimed design.
